NON-LETHAL WEAPON PRODUCING A LIQUID SPRAY

Alan L. Litman, Pittsburgh, Pa., and Dennis K. Hackbarth, Lima, Ohio, assignor to Bangor Punta Operations, Incorporated, New York, N.Y., a corporation of New York

Filed Apr. 8, 1969, Ser. No. 16,623

Term of patent 14 years

Int. Cl. D22—02

U.S. Cl. D22—3

FIG. 1

FIG. 2

FIG. 3

FIG. 4

FIG. 1 is a perspective view illustrating the front face, one side, and the top of the non-lethal weapon producing a liquid spray, showing our new design.

FIG. 2 is a side view showing the opposite side of the weapon.

FIG. 3 is a front elevational view of the weapon and illustrating the liquid spray opening and nozzle, and

FIG. 4 is a rear elevational view showing the back of the weapon.

We claim:

The ornamental design for a non-lethal weapon producing a liquid spray, as shown.
